PILE SPLICE

Knox Kershaw and Royce Kershaw,
Montgomery, Ala.

Application June 11, 1946, Serial No. 675,967

6 Claims. (Cl. 61—53)

1

This invention relates to piling construction and particularly to means for repairing piling that has been eaten away by rot, marine insects, and/or corrosion, which often occurs, particularly in salt water. One of the objects of our invention is to provide an improved splice for connecting steel piling to wood in making such repairs.

A further object of our invention is to provide splicing means for repairing piling which shall be adapted for connecting a new section of steel piling to an existing wood pile in such a way that the steel section shall be rigidly connected to the wood piling and shall be protected against corrosion.

A more specific object of our invention is to provide an improved splice for connecting a steel pile to a wood pile which shall be especially adapted for enclosing in concrete and thereby constituting a reinforcing for the concrete.

In the prior patent to John Knox Kershaw, No. 2,013,214, dated September 3, 1935, there is shown, described and claimed a method for repairing existing wood piling in which the defective portion of the wood piling between the mud line and solid wood above the water level was cut away and a concrete pile section interposed to replace the cut away wood pile section, together with end portions on the concrete section telescoping over the remaining portions of the wood pile. The present invention contemplates employing a steel section between the wood pile and the superstructure instead of employing a concrete section and the upper end of the wood pile, the steel section having a novel splice for connecting it to the wood pile below the mud line.

Our invention still further contemplates the novel installation and arrangement of parts illustrated in the accompanying drawings, forming a part of this application, in which

Fig. 1 is a view showing a construction in which an old wood pile has been replaced by a steel pile in accordance with our invention and the latter repaired by interposing a new steel section;

Figs. 2 and 3 are views taken at right angles to each other of the splice for connecting the steel pile to the wood pile;

Figs. 4 and 5 are similar views drawn to a reduced scale from Figs. 2 and 3; and

Fig. 6 is a detail sectional view on a reduced scale taken along line VI—VI of Fig. 2.

Referring now to the drawing for a better understanding of our invention, we show a marine construction involving a superstructure 10 which may be a wharf, bridge, building, or any other construction supported over water and compris-

2

ing stringers 11 having suitable decking 12 thereon. The superstructure is supported by piling, and in the illustration we show the sound portion 13 of the original wood piling left in place, it being assumed that the portion thereof above the mud line has been destroyed by rot, marine insects, or the like. Interposed between the wood piling 13 and the superstructure 10 are our improved repair sections which are comprised of steel beams 14, preferably in the form of H sections. At the upper end of the repair section, we provide plates 16 upon which the superstructure rests and at the lower end a splice for joining the steel section to the existing wood piling which splice forms an important feature of our invention.

In the form shown in Figs. 2 and 3 of the drawings, our improved splice comprises a plate 17 which is preferably circular in form, secured to the lower end of the steel repair section 14 and resting on the upper end of the existing wood piling. Surrounding the plate 17 is a sleeve 18 in the form of a steel plate rolled to fit about the circular plate 17. At the lower end of the sleeve 18 is a flared portion 20 which aids in placing the splice over the upper end of the existing wood pile. A plurality of longitudinally extending reinforcing plates 19 join the sleeve 18 to the steel repair section 14. These plates are preferably four in number and are disposed edgewise to the sleeve and to the repair section and are welded to both the upper ends of the plates extending inwardly to be attached to the repair section 14. The plates 19 are provided with holes 21 for suitable brace rods 22 having their upper ends secured to brackets 23 of adjacent sections and being provided with turn-buckles 24 for tightening them. The sleeve 18 is provided with holes 26 in the side thereof through which drift pins 27 are driven to secure the sleeve to the upper end of the wood piling 13. Also, I preferably provide barbs 28 on the inside of the sleeve which engage the wood piling as the sleeve is driven down over it. After the splice is in place, it is preferably stabilized by grout or neet cement which may be pumped in around the upper end of the wood piling to fill any voids. Also, the steel section is preferably provided with a concrete encasement 29 which extends from a point below the mean low water level to a point above the mean high water level, as shown.

The splice shown in Figs. 4 and 5 comprises a plate 31 secured to the lower end of the steel repair section 14 having a sleeve 32 rolled to fit about the plate and over the upper end of the

wood piling 13. Spaced below the upper sleeve or ring 32 is a lower sleeve or ring 33 of approximately the same diameter as the upper ring 32 and which fits about the upper end of the wood piling 13. The rings 32 and 33 are joined together by means of reinforcing members 34, preferably formed of T bars, which are bent inwardly as shown and are joined by welding at their upper end to the steel repair section 14. According to this modification, the upper plate 31 is provided with holes for the reception of drift pins 36 which are driven into the upper end of the wood pile 13. Barbs 37, in accordance with this modification, are provided on the reinforcing bars 34, near the lower ends thereof, to engage the wood pile. In addition to these securing means, we may drive a wedge 38 between the lower ring 33 and the wood pile 13.

As in the previous modification, when the splice is installed, grout of neet cement should be pumped in around it to stabilize the lower end of the repair section with respect to the wood piling as indicated at 40, and also to fill all voids between the parts of the splice and the upper end of the wood piling. We thus provide a rigid connection between the steel repair section and the upper end of the wood piling.

From the foregoing, it will be observed that our improved steel repair section can be interposed between the imperishable wood section below the mud line and the superstructure, without disturbing the superstructure. Inasmuch as the principal zone of attack for corrosion of metal is at the water line, the reinforced concrete encasement surrounding the steel repair section at that point fully protects it and we thus provide a relatively long life construction. Furthermore, it will be seen that the connection between the splice at the lower end of the repair section and the upper end of the existing wood pile is extremely rugged and not liable to become displaced.

While we have shown our invention in but two forms, it will be obvious to those skilled in the art that it is not so limited, but is susceptible of various other changes and modifications, without departing from the spirit thereof, and we desire, therefore, that only such limitations shall be placed thereupon as are specifically set forth in the appended claims.

What we claim is:

1. In a repair means for a marine structure including a superstructure and wooden piling which has been destroyed above the mud line, a repair section in the form of a steel beam interposed between the superstructure and the existing wood piling below the mud line, a splice comprising a circular metal plate secured to the lower end of the steel section and resting on the upper end of the wood pile, a sleeve secured to the plate and surrounding the upper end of the wood pile, longitudinally extending reinforcing members joined to the sleeve and to the repair section, and securing means coacting between the splice and the wood piling.

2. In a repair means for a marine structure including a superstructure and wooden piling which has been destroyed above the mud line, a repair section in the form of a steel beam interposed between the superstructure and the existing wood piling below the mud line, a splice comprising a circular metal plate secured to the lower end of the steel section and resting on the upper end of the wood pile, a sleeve secured to the plate and

surrounding the upper end of the wood pile, longitudinally extending reinforcing members joined to the sleeve and to the steel beam, securing means coacting between the splice and the wood piling, and a cement encasement surrounding the lower end of the steel section and the splice.

3. In a repair means for a marine structure including a superstructure and wooden piling which has been destroyed above the mud line, a repair section in the form of a steel beam interposed between the superstructure and the existing wood piling below the mud line, a splice comprising a circular metal plate secured to the lower end of the steel section and resting on the upper end of the wood pile, a sleeve secured to the plate and surrounding the upper end of the wood pile, longitudinally extending reinforcing members joined to the sleeve and to the steel beam, securing means coacting between the splice and the wood piling, a cement encasement surrounding the lower end of the steel section and the splice, and a second cement encasement surrounding the steel section at the water line.

4. In a repair means for a marine structure including a superstructure and wooden piling which has been destroyed above the mud line, a repair section in the form of a steel beam interposed between the superstructure and the existing wood piling below the mud line, a splice comprising a circular metal plate secured to the lower end of the steel section and resting on the upper end of the wood pile, a sleeve secured to the plate and surrounding the upper end of the wood pile, longitudinally extending reinforcing members joined to the sleeve and to the steel beam, securing means coacting between the splice and the wood piling, a cement encasement surrounding the lower end of the steel section and the splice, a second cement encasement surrounding the steel section at the water line, and brace connecting means at the upper and lower ends of the repair section.

5. In a repair means for a marine structure, a splice for connecting a steel repair section to an existing wood pile comprising a transverse plate secured to the lower end of the steel section and resting on the upper end of the wood line, a downwardly extending sleeve secured to the plate and surrounding the upper end of the wood pile, and longitudinally extending reinforcing plates joined to the sleeve and to the steel section.

6. A repair means in accordance with claim 4 in which the reinforcing members are T shaped in cross section and are bent toward the steel beam to be secured thereto.
